Primary Examiner — Mark Goodwin

CLAIM

(57) The ornamental design for an operator cab, as shown and described.

DESCRIPTION

FIG. 1 is a front perspective view of an operator cab according to the design;

FIG. 2 is a left-side view of the operator cab of FIG. 1;

FIG. 3 is a right-side view of the operator cab of FIG. 1;

FIG. 4 is a front view of the operator cab of FIG. 1;

FIG. 5 is a rear perspective view of the operator cab of FIG. 1;

FIG. 6 is a top view of the operator cab of FIG. 1;

FIG. 7 is a bottom view of the operator cab of FIG. 1; and,

FIG. 8 is a front perspective view of the operator cab of FIG. 1, installed on a crane to illustrate environment.

The broken lines in the drawings are for the purpose of illustrating portions of the operator cab that form no part of the claimed design. Portions of the operator cab shown in broken lines form no part of the claimed design. Further, the crane shown in broken lines in FIG. 8 is environment only and forms no part of the claimed design.

1 Claim, 8 Drawing Sheets
